UNITED STATES PATENT OFFICE.

LE BARON C. COLT, OF BRISTOL, RHODE ISLAND, ASSIGNOR TO NATIONAL INDIA RUBBER COMPANY, A CORPORATION OF RHODE ISLAND.

DESIGN FOR A SHOE.

49,573.

Specification for Design.

Patented Aug. 29, 1916.

Application filed April 6, 1915. Serial No. 19,559. Term of patent 14 years.

To all whom it may concern:

Be it known that I, LE BARON C. COLT, a citizen of the United States, residing in the city of Bristol, county of Bristol, and State of Rhode Island, have invented a new, original, and ornamental Design for a Shoe, of which the following is a specification, reference being had to the accompanying drawing, in which—

I claim:

The ornamental design for a shoe as shown.

LE BARON C. COLT.
